5 Claims. (Cl. 29—177)

This invention relates to watertight watchcases comprising a cover member fitting a lodging of a watchcase body member to close the watchcase tightly and in particular to the methods for opening such a watchcase.

The watchcases of the type more particularly considered here usually comprise a one-piece metallic section constituting both the case band and the bottom and the cover member provided for closing the watchcase consists of the glass.

In order to open these watchcases the glass has thus to be removed. Since the latter has to ensure a tight closure of the watchcase, its removal, however, involves some difficulties.

In a first group of watchcases of the type above-mentioned, which are known in the art, the glass comprises an outer flange extending around the glass sleeve tightly fitting the corresponding lodging of the metallic watchcase section constituting the case band and the bottom. This glass can be removed by inserting a blade, such as for instance a knife blade, successively at different points under the glass flange and by lifting the glass progressively out of its lodging. These known watchcases have, however, the drawback that the peripheral glass flange soonly becomes injured, because the glass used with watertight watches is organic. It occurs indeed that the blade used to open the watchcase causes the glass flange to become jagged.

To avoid this drawback independent metallic bezels have been used in the watchcases of the type referred to above, said bezels comprising an inner rim extending under a glass shoulder. To remove the glass and open the watchcase one proceeds as disclosed above. The blade is here, however, inserted under the metallic bezel and not under a glass flange and the bezel distributes the lifting force exerted by the blade regularly on a relatively large glass flange portion so that this glass flange is not submitted to exceedingly high stresses concentrated in one point and does therefore no longer risk to become jagged.

Since the metallic bezel of these known watchcases has no other function as that to allow removing the glass without damaging the same, the watchcases comprising such a bezel have to be made thicker than necessary thus causing an unaesthetic effect. It is of course well known to those skilled in the art that a watch movement having a relatively great thickness in its center portion can nevertheless be mounted in a watchcase so as to give the impression of a very flat watch if the peripheral part of the watchcase is made very thin. Now, the extra bezel above-mentioned has the drawback to give a watch with a movement having a predetermined thickness the appearance of being thicker than a watch with a movement which is thicker than said predetermined thickness but the casing of which does not comprise an extra bezel.

To avoid this drawback watchcases have been made with a glass comprising a portion protruding from the metallic body member of the watchcase, said protruding glass portion being arranged so that it may be gripped by means of a tool adapted for exerting not an axial but a radial pressure on the glass. A great variety of tools have even been put on sale to enable removing the glass in that way. One of these tools chiefly comprises a split ring which can be set around a cylindri-

2

cal glass portion and then closed under strong pressure by means of tongs. Another known tool provided for the same purpose comprises a plurality of jaws (15 to 20) each located on a lever mounted for rocking motion about an axis which is perpendicular to that of the watchcase when the jaws of said tool surround the cylindrical surface of the glass protruding from the watchcase metallic section. A movable core of said tool enables causing all these levers to rock simultaneously, to grip the glass between said jaws and to exert a strong radial pressure thereon.

If a glass arranged so that it can be removed upon exerting a radial pressure thereon permits to avoid the drawbacks involved by a glass which has to be removed by an axial force exerted thereon, it nevertheless involves further drawbacks. Thus, when a strengthening ring is located within the glass sleeve set in the lodging of the metallic watchcase body for pressing this sleeve in a radial direction against the cylindrical wall of said lodging, in order to ensure a satisfactory closure of the watchcase, it may occur that the pressure exerted on the glass by a tool comprising a split ring solicits the strengthening ring beyond its limit of elasticity, if said tool is not manipulated very carefully. In such an event, the strengthening ring would be subjected to a permanent deformation and would then be unable to press the glass sleeve satisfactorily against the wall of its lodging when the watchcase would be closed again. With the tool comprising a plurality of jaws as indicated above the glass is exposed to the same danger. Moreover, if said jaws are pressed too strongly against the glass, they produce markings on the periphery of the latter.

Further tools are also known in the art for opening a watchcase by gripping a glass portion protruding from the metallic piece of the watchcase. In this case the protruding glass portion is not made with an outer smooth cylindrical surface but either with a truncated conical surface which opens toward the outside of the watchcase or with a cylindrical surface provided with an annular groove matching with a corresponding rib of the removing tool. These known glasses have, however, the drawback that they also increase the thickness of the watchcase at its periphery. Moreover, they have still the drawback, that they do not have a standard shape and cannot therefore be replaced by every watchmaker.

It is also known in the art to open a watchcase of the type referred to above by applying a suction cup on to the glass and by producing then a vacuum above the glass in order to increase its curvature and to close its peripheral sleeve extending within the lodging of the metallic watchcase piece. The pressure which can be exerted on the glass by this method cannot of course exceed one atmosphere. In order that so small a pressure can produce a sufficient deformation of the glass, the latter must have relatively large sizes and be made very thin. Moreover, this suction method does not enable removing a glass provided with a strengthening ring. Finally, a glass which jumps out of its lodging under a pressure which does not exceed one atmosphere has still the drawback that it is not safely fixed to the metallic piece of the watchcase.

It is therefore an object of this invention to provide a method for opening a watchcase tightly closed by a cover member fitting a lodging of a watchcase body member, which enables removing said cover member without providing the same with means permitting to grip it, said cover member being secured to the watchcase body member in as strong a manner as may be required.

It is also an object of this invention to remove the cover member tightly closing a watchcase by increasing the watchcase inner pressure until the cover member jumps out of its lodging.

Still another object of the invention consists in pressing a limited amount of air into a watchcase tightly closed by a cover member fitting a lodging of a watchcase body member, thereby producing a pressure increase inside the watchcase, which is sufficient in order to cause said cover member to jump out of its lodging.

Further objects of the invention will still become apparent in the course of the following description.

The inner pressure of the watchcase can be increased from outside the same for instance by means of a pump introducing air through an opening provided through the wall of the watchcase, said opening being usually tightly closed by a removable stopper.

With a watch comprising a winding and hand setting stem in two pieces, one of the same extending within a passageway of the watchcase body member and being removably connected by resilient means to the second stem piece which extends within the movement, the passage through which air can be introduced into the watchcase in order to increase the inner pressure thereof will of course be the stem passage. With such a watch the method according to the invention can be performed by removing first the outer stem part together with the crown, by connecting the outlet of a pump to the stem passage and by increasing the inner watchcase pressure by means of said pump.

The method according to the invention will now be illustrated by an example disclosed with reference to the accompanying drawings.

In the drawings:

FIG. 1 is a part diametrical section of the watchcase which can be opened by the method according to the invention, and

FIG. 2 diagrammatically illustrates how the method according to the invention can be carried out.

The movement 1 of the watch represented in FIG. 1 is located in a watchcase comprising a single metallic piece 2 which constitutes both the case band and the bottom. This piece 2 is formed with a shoulder 3 serving as support for the outside flange 4 of the movement base-plate. Piece 2 is further provided in its upper portion with a lodging 5 which serves to receive the glass 6. The latter closes the casing of the watch represented. For that purpose it comprises a cylindricical sleeve 7, which enters the lodging 5 and which is pressed against the cylindric wall of this lodging by a strengthening ring 8. The casing of the watch represented is finally provided with a passageway 9 in which a pipe 10 is tightly inserted. A first piece 11 of a winding and hand setting stem extends within passage 9 and pipe 10. A usual winding crown (not shown) is fixed to the stem piece 11 and is provided with a watertight gasket extending between a crown portion and pipe 10. The inner end of piece 11 is split lengthwise and provided with a transversal bore so as to form two resilient jaws 12 and a lodging 13. A second stem piece extends within movement 1. This second stem piece comprises a flat portion 14 protruding from the movement and ending in a thicker portion 15 normally extending within bore 13. The two stem pieces are connected to each other by portion 15 and bore 13 so that they are simultaneously both driven in rotation and shifted axially upon rotating the crown or moving the same in axial direction from its winding position into its hand setting position or vice versa.

The stem piece 11 is split over a sufficient length in order to form jaws 12 which have such an elasticity that both pieces of the stem can be disconnected from each other upon exerting a strong axial thrust on the crown.

Stems of the type described are well known in the art. The coupling means of the two stem pieces are adjusted in such a manner that the force which must be exerted on the crown in order to disconnect the outer stem piece from the inner one is a great multiple of that which must be exerted on the crown in order to cause the same to pass from its winding position to its hand setting position. The

multiple usually chosen can be as great as ten without exposing the stem portions ensuring the coupling of the two stem pieces from any damage due to a stress exceeding the limit of elasticity when the two stem pieces are disconnected from one another or connected again to each other.

To open the casing of the watch described the crown is first removed by exerting an axial pull on the latter, which is strong enough in order to cause the jaws 12 to move away from one another and to leave the thicker portion 15. Pipe 10 is then connected to the outlet of a pump or of any other installation, apparatus or device arranged for increasing the air pressure within the cavity of the watchcase. This installation, apparatus or device is then actuated so as to increase the air pressure within the casing until the glass 6 jumps out of its lodging. A pressure of 3 to 4 atmospheres is usually sufficient in order to urge the glass 6 out of its lodging.

A tool which can advantageously be used to perform the method according to the invention is represented diagrammatically in FIG. 2. This tool consists of a pump provided with a valve. It comprises a body member 16, a nozzle 17 and an actuating button 18 connected to a piston. After having removed the crown in the manner described above, pipe 10 is introduced into nozzle 17 and button 18 is pressed sometimes until the pressure within the watchcase causes the glass 6 to jump out of its lodging. In this manner no violent air blow is produced within the watch movement so that there is no risk to blow the lubricating oil from the bearings away or to injure the hair-spring at the moment at which the glass leaves its lodging. The air remaining in the pump cylinder of the tool described and which suddenly enters the watch movement under the pressure exerted thereon by button 18 when the watchcase opens is indeed very small.

Instead of a tool comprising a pump of very small capacity one could also resort to a tool which can remove the glass in a single pumping operation. With such a tool the pump capacity should however be chosen in function of the volume of the watchcase cavity in order to avoid a strong air jet into the watch movement when the watchcase opens. A tool comprising a pump, the cylinder of which has a volume substantially equal to about 25 cm.³ (cylinder diameter: 2 cm.; height: 8 cm.) gives satisfactory results.

The method according to the invention has the advantage to permit opening watchcases of any sizes. In order that this method can be performed practically, the watch needs only be provided either with a stem in two pieces of the type disclosed above or with a particular passageway extending through the wall of the watchcase and being tightly closed by means of a removable stopper.

Another advantage of the method according to the invention is due to the fact that this method permits manufacturing a watchcase having a very flat appearance. For this purpose it is sufficient to provide a lodging 5, the depth of which is equal to that of the lodgings usually provided in the known casings with removable bottoms and arranged for receiving a glass carrying a strengthening ring. It will be observed that the glass 6 has not to be arranged so as to offer a grip accessible from outside the watchcase. The upper glass surface can thus be made flush with the upper portion of the watchcase body member as with the known casings provided with a removable bottom.

Further modifications in performing the method disclosed above will still appear obvious to those skilled in the art without departing from the spirit of the invention or sacrificing the advantages thereof.

I claim:

1. A method for opening a watchcase tightly closed by a cover member fitting a lodging of a watchcase body member, comprising the steps of connecting the watchcase cavity to an air chamber having a predetermined

volume, and urging the air from said chamber to said cavity, the predetermined air volume of said chamber thereby producing inside the watchcase a pressure increase strong enough to cause the cover member thereof to jump out of its lodging.

2. A method for opening a watchcase tightly closed by a cover member fitting a lodging of a watchcase body member and a winding and hand setting crown fitting a pipe tightly inserted in a passageway provided through the wall of the watchcase, comprising the steps of removing the crown and pressing through the pipe associated therewith a limited amount of air into the watchcase, thereby producing a pressure increase therein which is sufficient in order to cause the cover member thereof to jump out of its lodging.

3. A method for opening a watchcase tightly closed by a cover member fitting a lodging of a watchcase body member and by a winding and hand setting crown fitting a pipe tightly secured to the watchcase, comprising the steps of removing the crown, connecting the pipe associated therewith to an air chamber having a predetermined volume, and pressing the air from said chamber through

said pipe into the watchcase, thereby producing a pressure increase therein strong enough to cause the cover member thereof to jump out of its lodging.

4. A method according to claim 3, the cover member consisting of the glass.

5. A method for opening a watchcase tightly closed by a cover member fitting a lodging of a watchcase body member, comprising the steps of connecting the watchcase cavity to an air chamber and urging air from said chamber into said cavity thereby producing inside the watchcase a pressure increase strong enough to cause the cover member thereof to jump out of its lodging.
